UNITED STATES PATENT OFFICE

ARTHUR K. BAKER, OF CHICAGO, ILLINOIS, ASSIGNOR TO HEGGIE SIMPLEX BOILER COMPANY, OF JOLIET, ILLINOIS, A CORPORATION OF ILLINOIS

DRAFT-DOOR APPARATUS

Application filed April 17, 1929. Serial No. 355,874.

This invention relates to improvements in boilers and has special reference to improved draft door operating and controlling apparatus for boilers.

5 The boilers to which this invention especially applies are of the kind disclosed and claimed in my co-pending application, filed March 5, 1929, Serial No. 344,358. These boilers are provided with a transversely extending refractory chamber in the upper part of the fire box, and air is admitted through openings in each side of the boiler into the ends of this chamber. Doors are provided, one at each side of the boiler for 10 controlling the admission of air through these openings, and this present invention has to do especially with means for controlling these doors.

It is desirable that these doors be opened 20 and closed simultaneously and from a single point. To accomplish this, I provide a single control handle located at one side of the boiler in a convenient place, connecting this handle with both of the doors, and for this 25 purpose I provide a pipe extending transversely through the body of the boiler and sealed into the side walls thereof. In the embodiment of my invention which I have chosen to illustrate it, I connect the control 30 handle with the two doors by means of a divided chain, one part of which extends through the boiler by means of the sealed-in pipe referred to.

The invention will be more readily understood by reference to the accompanying drawings forming part of this specification and in which:

Fig. 1 is a side elevation of a boiler equipped with a draft door operating mechanism embodying the invention in one form;

Fig. 2 is a vertical transverse section on the line 2—2 of Fig. 1;

Fig. 3 is a perspective view of the operating handle and related parts;

Fig. 4 is a detail vertical section on the line 4—4 of Fig. 3;

Fig. 5 is a fragmentary vertical section on the line 5—5 of Fig. 1; and

Fig. 6 is a section similar to Fig. 5 on the line 6—6 of Fig. 2.

In said drawings, 1 illustrates a horizontal tubular boiler having an upper cylindrical part 2 for containing the boiler flues 3 and a lower rectangular part containing the fire box 4. The boiler is made up of an outer U-shaped shell 5 and an inner U-shaped shell 6. The cylindrical part 2 of the boiler is defined by the upper parts of the inner and outer shells, the upper part of the inner shell forming a crown sheet 7 for the fire box 4.

In the upper part of the fire box, about midway between its ends, is provided a transversely extending hollow baffle wall 8 made up of refractory side parts 9 and a refractory bottom part 10. This wall is supported on transversely extending water tubes 12. The refractory chamber 13 formed by the hollow wall 8 extends across the fire box from side to side. The depending parts of the inner and outer shells are spaced apart to form side water legs 14, and opposite the ends of the chamber 13, openings 15 are provided, extending through the side water legs for the purpose of admitting air into the chamber 13 at its ends. The wall 8 is provided with openings 16 in its forward side for the admission of hot gases from the forward end of the fire box for admixture with the air entering through the end openings 15 and with openings 17 in its bottom for the emission of the mixed air and gases into the fire box.

The air admission openings 15 are formed by welding header rings 18 between the inner and outer shells, and these openings are controlled by doors 19 and 20, one at each side of the boiler. The doors 19 and 20 are just alike; they are hingedly mounted at their upper ends to swing upwardly and outwardly. The doors 19 and 20 are mounted on suitable box-like members 21 and 22, respectively, which extend the openings 15 outwardly. The doors 19 and 20 close by gravity, and means are provided for swinging the doors up for opening them.

In order to avoid unsightly chains, levers, or other apparatus extending above the boiler, I provide a transversely extending pipe 23 extending across the cylindrical part of the boiler above the doors 19 and 20 and through which a door operator can extend to facilitate the opening and closing of the doors.

tate the simultaneous operation of the doors from a single point of control. The pipe 23 is sealed into the side walls of the boiler.

I arrange a draft door operating handle 5 24 at the front of the boiler at one side, adapted to be connected to the doors 19 and 20 by a chain 25.

Above the door 20, which is on the same side of the boiler as the operating handle 24, 10 the end of the pipe 23 is provided with a three-way elbow 26 having one nozzle 27 extending horizontally and screwed into the pipe 23, another nozzle 28 extending down toward the door 20, and a third nozzle 29 extending toward the front end of the boiler.

Above the opposite door 19, the end of the pipe 23 is provided with an elbow 30 pointed down toward the door 19.

The chain 25, which is connected to the 20 handle, is divided between the handle and the elbow 26 into two branches 31 and 32, one of which leads to the door 20 and the other to the door 19 through the elbows and pipe 23.

For cooperation with the handle 25 to retain the doors in adjusted positions, I provide a plate 33 fixed to the side of the boiler. The plate 33 is provided with a guide hole 34 near its upper end for the chain 25 and with several pairs of projections 35 adapted to be 30 engaged by the handle 24 for retaining the doors in adjusted positions in an obvious manner.

As many modifications of the invention will readily suggest themselves to one skilled 35 in the art, I do not limit or confine the invention to the specific details of construction and specific combinations of devices and parts herein shown and described.

I claim:

10 1. A boiler provided with an air inlet opening at each side, a hollow stay extending through the boiler above said openings, doors for controlling said openings, a door operating handle arranged near the front of the boiler at one side, a door operator extending from the handle to each of said doors, the part of the operator connected with the door on the opposite side of the boiler passing through said hollow stay, and means for retaining the handle in different adjusted positions.

2. A boiler provided with an air inlet opening at each side, a hollow stay extending through the boiler above said openings, doors 55 for controlling said openings, a control plate secured to one side of the boiler near its front, the plate provided with a plurality of pairs of projections, a handle for engagement with said projections, a flexible door operator extending from the handle to the door on the same side of the boiler, a branch flexible door operator connected to the first said operator and extending through the hollow stay to the other door.

60 3. A boiler provided with an air inlet open-

ing at each side, a hollow stay extending through the boiler above said openings, a three-way elbow on one end of said hollow stay, a control plate secured to the boiler near its front end and on the same side as said three-way elbow, a control handle for co-operation with said plate, means on the plate for permitting a plurality of engagements of the handle with the plate, a chain leading from the handle through said three-way elbow to the door below same, a branch chain connected with the first chain between the plate and the elbow and leading through the elbow and through said hollow stay to the opposite door, as and for the purpose de- 80

75 4. A boiler having a combustion chamber and provided with an opening at each side for admitting auxiliary air to the combustion chamber, doors controlling said openings, a protective conduit extending transversely through the boiler above said doors, a single door control device, a door operating means connecting said device with both the doors and passing through said conduit. 90

5. A boiler having a combustion chamber and provided with an opening at each side for admitting auxiliary air to the combustion chamber, doors controlling said openings, a protective conduit extending transversely 95 through the boiler above said doors, a single door control device arranged at one side of the front of the boiler, a door operating means connecting said device with both the doors and passing through said conduit. 100

6. A boiler provided with an air inlet opening at each side, a hollow stay extending through the boiler above said openings, doors for controlling said openings, a door operator extending from a single point of control to each of said doors, the part of the operator connected with one of said doors passing through said stay, and an operator adjuster at said single point of control for opening and closing both said doors simultaneously. 110

In witness that I claim the foregoing as my invention, I affix my signature this 11th day of April, 1929.

ARTHUR K. BAKER.
